UNITED STATES PATENT OFFICE.

EUGENE D. DUMOND, OF WATERLOO, IOWA.

WASHING-MACHINE.

1,177,608.

Specification of Letters Patent.

Patented Apr. 4, 1916.

Application filed August 6, 1915. Serial No. 44,013.

To all whom it may concern:

Be it known that I, EUGENE D. DUMOND, a citizen of the United States of America, and a resident of Waterloo, Blackhawk county, 5 Iowa, have invented certain new and useful Improvements in Washing-Machines, of which the following is a specification.

My invention relates to improvements in washing machines, and the objects of my 10 improvements are, first, to provide an improved actuating mechanism for the vacuum stirring head or plunger of such a machine, and second, to associate with such mechanism other mechanism also driven thereby 15 for rotating the rotary tub. These objects I have accomplished by the means which are hereinafter described and claimed, and which are illustrated in the accompanying drawings, in which:

20 Figure 1 is a side elevation of my improved washing machine, with parts broken away or sectioned. Fig. 2 is a front elevation of said machine, with the tub and some other parts shown in cross section, and other 25 parts being broken away. Fig. 3 is a top plan view of said machine. Fig. 4 is an enlarged side elevation of the cam-casing and its connections to the plunger-shaft. Fig. 5 is a side elevation of the cam-casing and 30 cam, with the side plate removed.

Similar numerals of reference denote corresponding parts throughout the several views.

My improved washing machine has a rotatable tub 32 whose upper end is flanged outwardly at 34, with the flange resting upon a plurality of roller-bearings seated in a depending ring 35 fixed to the under face of the tub top 42. A ring 33 is fixed within 35 the top of said tub to reinforce it at that place. The machine has legs 48 connected by cross bars 49. The top 42 is supported on said legs, and has an oblong opening provided with a closure 43 supported on the 40 hinges 44, and having detachable catch-members 45 and 46, to detachably secure it to said top.

Referring to Fig. 2, the numeral 4 denotes a horizontal plate supported on standards 6 45 and 51, said standards rising from a base-plate fixedly, said plate having integral tubular part depending through an opening in the top 42 to act as a bearing for the plunger-sleeve 2. The sleeve 2 is slidably mounted upon a rod or fixed shaft 3 depending for a distance from the under side of said plate

4, and a vacuum plunger-head 1 of conical shape is affixed to the lower end of the sleeve within the tub eccentric to its center or axis.

The numeral 7 denotes a cam-casing of oblong form, provided on one outer face with vertically-spaced orificed lugs 8 and 9. The plunger-sleeve 2 passes through the alined orifices of said lugs, and a collar 10 is secured on said sleeve just above the lower lug 60 9, by means of a set-screw 11. The lugs 8 and 9 are mounted slidably on said sleeve 2. A coiled spring 12 is mounted on said sleeve between the collar 10 and the upper lug 8 65 to engage both. The cam-casing 7 has an open right-hand end closed by means of a face-plate 13, orificed to receive the rotary shaft 16 which latter has a circular cam 14 fixed on its end within said casing. An anti-friction ring 15 is mounted rotatably about 70 the circumferential edge of said cam to form anti-friction contacting means therefor against the inner walls of said casing. The horizontal shaft 16 has its other end mounted in the bearing 19 on the machine top 42, 80 and carries a sprocket wheel 17. The top 42 has an oblong opening 47 below the sprocket-wheel 17.

A cross-bar 41 secured in the lower part of the machine below the tub 32, has a short upright body 40 with an upwardly opening sprocket adapted to receive a depending shaft 38 extending axially from said tub and resting upon an anti-friction ball 39. A bevel gear wheel 37 is mounted on the bottom of the tub coaxially with said shaft. A horizontal shaft 21 has its left-hand end mounted in a bearing opening in the body 40 and has a bevel pinion 42 secured thereon and in mesh with the wheel 37. The right-hand end of said shaft is mounted in a bearing opening in a hanger 52, and carries a sprocket-wheel 20. A sprocket-chain 18 connects the two sprocket-wheels 17 and 20, passing through the opening 47 in the machine top 42. A shaft 29 has its left-hand end rotatably mounted in a bearing in said hanger 52, while its right-hand end is mounted in a bearing in a cross-piece 50 connected between two of the legs 48. On 85 said shaft are secured a relatively small sprocket wheel 30 and a fly-wheel 31, the sprocket-wheel intermeshing with the sprocket-chain 18. A socket 25, containing a hand lever 28, is pivoted at 26 to a lug 27 90 on the machine frame. A curved link 23 is pivotally connected between a stud 24 on

said socket 25, and a crank-pin 22 on the sprocket-wheel 20.

When the hand-lever is oscillated, the link 23 rotates the sprocket wheel 20, so that the 5 chain 18 causes the rotation of the pinion 30 and fly-wheel 31, and also the sprocket wheel 17, shaft 16 and cam-wheel 14. The fly-wheel is driven at a higher rate of speed than the sprocket-wheel 17 and cam-wheel 10 14. The rotating shaft 21 causes the pinion 42 to rotate the bevel-gear 37 and tub 32 at a relatively low speed. The cam-wheel 14, as indicated in Fig. 5, imparts a vertically reciprocating movement to the cam-casing 7.

15 Referring now to Fig. 4, it will be seen that when the cam-casing 7 descends, its lug 8 will bear against the yieldable spring 12 in pushing down the sleeve 2 and plunger-head 1. In case that any of the contents of 20 the tub 32 happen to be bunched up under said plunger-head 1, said spring 12 will yield enough to prevent the head from tearing or injuring the fabric. When the cam-casing rises, its lug 9 engages and lifts upon the 25 collar 10 fixed to the sleeve 2, thereby carrying up the plunger-head to its upper limit of movement. The tension of the spring 12 may be varied by adjustably securing the collar 10 upon said sleeve 2.

30 In the operation of the machine, the tub 32 is rotated simultaneously with the up-and-down reciprocation of the plunger-head 1, which is of the vacuum type. Said plunger-head, being oscillated in said tub eccentrically relative to its axis, acts successively upon the contents of the tub as the latter rotates, and thus agitates and manipulates said contents very thoroughly.

Various changes may be made in the 40 details of the mechanism, their form, dimensions and arrangement, without departing from the principles of this invention.

Having described my invention, what I claim as new, and desire to secure by Letters Patent, is:

1. In a washing-machine, a frame, a tub 50 rotatably mounted therein, a fixed shaft on said frame depending into said tub, a sleeve slidable on said shaft and provided with a stirring-head fixed on its lower end, a cam-casing having vertically spaced orificed lugs slidably mounted upon said sleeve, a rotata-

ble cam in said casing, a collar adjustably secured upon said sleeve above the lower lug to limit the movement of the cam-casing 55 thereon upwardly and a coiled spring mounted upon said sleeve and engaged between said collar and the uppermost lug and adapted to yieldingly cushion and limit the movement of the stirring-head on its down- 60 stroke.

2. In a washing-machine, a frame, a tub mounted therein, a fixed shaft depending into said tub, a sleeve slidable on said shaft and provided with a fixed stirring-head on 65 its lower end, a cam-casing connected to said sleeve movably and resiliently to cushion the stirring-head on its down-stroke only, a rotatable cam mounted in said casing and adapted to oscillate it with said sleeve 70 and stirring-head and means for adjusting the tension of the said resilient connection.

3. In combination, a frame, a hollow body rotatably mounted therein, a reciprocatory body extending into said hollow body, a 75 driving-shaft mounted rotatably in said frame, operative elements connected between said driving-shaft and said hollow body adapted to rotate the latter, a counter-shaft, a sprocket-wheel on said driving-shaft, a 80 sprocket-wheel on said counter-shaft, a sprocket-chain connecting said sprocket-wheels, another shaft, a fly-wheel and a sprocket-pinion mounted on the last-mentioned shaft, said sprocket-pinion being in 85 mesh with said sprocket-chain and adapted to rotate the fly-wheel more rapidly than either of the said sprocket-wheels, and operative elements connected between the counter-shaft and said reciprocatory body adapt- 90 ed to reciprocate the latter.

4. In combination, a rotatable body, a reciprocatory body depending toward it eccentrically, a fly-wheel, and coacting power-transmission mechanism operatively connected between said rotatable body, reciprocatory body and fly-wheel adapted to actuate them simultaneously and uninterruptedly while rotating the fly-wheel at a higher rate of speed than either the rotatable 100 body or the reciprocatory body.

Signed at Waterloo, Iowa, this 3rd day of August, 1915.

EUGENE D. DUMOND.
